UNITED STATES PATENT OFFICE.

GEORGE A. HOLMES, OF NEWTON, MASSACHUSETTS, ASSIGNOR TO THE CONSOLIDATED FASTENER COMPANY, OF PORTLAND, MAINE.

MACHINE FOR SAWING KERFS.

SPECIFICATION forming part of Letters Patent No. 659,280, dated October 9, 1900.

Application filed February 5, 1900. Serial No. 4,036. (No model.)

To all whom it may concern:

Be it known that I, GEORGE A. HOLMES, of Newton, in the county of Middlesex and State of Massachusetts, have invented a new and useful Improvement in Machines for Sawing Kerfs, of which the following, taken in connection with the accompanying drawings, is a specification.

My invention relates to a machine for sawing kerfs in metallic blanks or eyelets designed for use as the socket members of separable fastenings; and its object is to provide a simple and effective machine adapted to saw either two or four kerfs in the blank, as may be desired.

The characteristic features of the machine and its details of construction will be fully described hereinafter, and defined in the appended claims, in connection with the accompanying drawings, which form a part of this specification, and in which—

Figure 1 is an elevation of the front side of a machine embodying the invention. Fig. 1^A is a detail view of the stripper employed with the machine. Fig. 2 is an elevation of the rear side of the machine. Fig. 3 is a section on the line 3 3 of Fig. 1. Fig. 4 is an end elevation of the machine, partly in section. Fig. 5 is a detail horizontal section of one of the saws and one of the blank-holders. Fig. 6 is a detail section of a portion of the blank-carrier, showing one of the blank-holders and devices connected therewith. Fig. 7 is a perspective view of a blank or eyelet formed with four kerfs, and Fig. 8 is a similar view of a blank or eyelet formed with two kerfs.

A A' designate a base and frame upon which the mechanism is supported, with suitable standards or brackets rising from the base and provided with bearings for shafts.

Upon one end of the shaft C is fixed a disk or carrier-wheel C², the periphery of which is formed with a series of radially-disposed sockets or pockets C³. The peripheral edge of the wheel between the pockets is grooved or slotted, as shown in Fig. 4, to allow the saws to enter, and the side edges of the periphery of said carrier-wheel are annularly recessed for a purpose hereinafter explained.

Upon the opposite end of the shaft C is mounted a gear-wheel meshing with a gear-pinion

mounted upon a stud projecting from the side of the base, upon which is also mounted a belt-pulley B', adapted to be driven by a belt B³. Within each of the pockets of the carrier-wheel is arranged a holder or mandrel C⁴, upon the outer ends of which the blanks L are fitted. Each of the mandrels is provided with a hub C⁴, (shown in Figs. 5 and 6,) located within slots formed in the wheel C². From each of the hubs C⁴ projects a pin D, adapted to be struck by a projection on the frame of the machine. At a point diametrically opposite the pin D on each of the hubs a pin or lug C⁶ projects, to each of which is secured one end of a coil-spring C⁵, the opposite ends of which are secured to the wheel C² by screws or other fastening devices. Adjacent to each of the slots a stop-block F is adjustably secured to the wheel, against which the pins D normally bear.

Z designates an angle-arm secured to the base and having a cam-surface E, against which the pins D strike as the carrier-wheel is revolved, thus partially revolving the blank-holders and the blanks carried thereby.

The horizontal portion of the angle-arm Z is formed with a longitudinal slot x to permit of the adjustment of the arm to move the cam E out of the path of the pins D when desired.

Upon the shaft S' is a circular saw S, held between clamping-washers and by a nut, and below the shaft S', in a suitable bracket-bearing, is a second saw-shaft T', also carrying a saw secured by washers and a nut. As illustrated in Fig. 2, these saw-shafts are revolved by a belt passing under the shafts and around an idler mounted upon the shaft C.

To hold the blanks while being operated upon, I provide three guards or keepers M, M', and M², which preferably consist of light spring metal. The upper guard M depends from a standard rising from the base, the lower guard M² is secured to the base, and the central guard M' is secured to an arm adjustably secured to the machine. These upper and lower guards are slotted to allow the saws to work through them. The guard M also serves to automatically move the eyelet to its proper seat in its pocket in case the operator fails to properly place it, it being understood that the eyelet is held in position by said

guards with a sufficient frictional contact with the end of the mandrel to insure the rotation of the eyelet by the mandrel when operated as hereinbefore described, but without being held in position by clamping.

The operation of the machine is as follows: The blanks or eyelets are placed within the sockets of the carrier-wheel by an attendant and are presented to the upper saw by the revolution of the carrier-wheel, which saws a kerf centrally across the end of the blank, as shown in Fig. 8. A further movement of the carrier causes the pin D of the nearest mandrel-hub to strike the cam E, which imparts a half-revolution to the mandrel, turning the blank correspondingly to present it to the lower saw in position to receive a kerf at right angles to the first one, making the four cuts or kerfs, as shown in Fig. 7. In case it is desired to make only two kerfs, as illustrated in Fig. 8, the angle-arm Z is adjusted to move the cam E out of the path of the pin D, so that no turning of the holder or mandrel is effected and the lower saw is not used. For the purpose of forming two kerfs a simple socket in the carrier-wheel to receive the blanks will suffice, the mandrels and their revolving devices not being required. The blanks after passing the saw or saws ordinarily drop by gravity into a suitable receptacle; but in order to insure the discharge of the blanks after the kerfing I employ a bifurcated stripper. (Shown in Figs. 1 and 1^A.) One end of this stripper is secured to the base of the machine and the bifurcated free end rests over the recessed edges of the carrier-wheel in position to engage the flanges of the blanks and strip them away from the wheel.

I claim—

- 40 1. In a machine for forming kerfs in blanks or eyelets, the combination with a non-clamping revoluble carrier formed with pockets to receive the blanks; a saw or saws for forming the kerfs, and means for continuously revolving the saw and carrier.
- 45 2. In a machine for forming kerfs in blanks or eyelets, the combination with a continuously-revolving carrier formed with peripheral pockets; mandrels arranged within the pockets to receive the blanks; saws for forming the kerfs; and means for imparting a partial revolution to said mandrels.
- 50 3. In a kerfing-machine, the combination with a continuously-rotating non-clamping disk formed with peripheral pockets, of cutting devices for forming the kerfs.
- 55 4. In a kerfing-machine, the combination with a rotary carrier having peripheral pockets to receive the blanks; means independent of the carrier for holding the blanks thereupon, and means for discharging the blanks after they are kerfed.
- 60 5. In a kerfing-machine, a revoluble non-clamping disk provided with peripheral pockets and saw-slits, in combination with a rotary saw.
- 65 6. In a kerfing-machine, a revoluble carrier

non-clamping disk provided with peripheral pockets, and slotted to accommodate a saw, in combination with a saw, and a blank-holding device.

7. In a machine for sawing kerfs or eyelets, a revolving carrying-disk provided with an edge narrower than the flange of the eyelet or blank to be kerfed, in combination with a stripper.

8. In a machine for sawing kerfs in eyelets, a disk provided with one or more spring-mandrels in combination with a cam, whereby the mandrel is turned.

9. In a machine for sawing kerfs in eyelets, a disk provided with mandrels having projecting spring-pins, in combination with spring-holders, whereby the eyelet is pressed onto the mandrel and caused to revolve with it.

10. A kerfing-machine comprising a rotating carrying-disk having a series of mandrels arranged radially on said disk and each adapted to receive and hold a blank, and present it to the kerfing-saws, mechanism for causing said mandrels to make partial rotations on their axes; and kerfing-saws arranged to kerf the said blanks.

11. A kerfing-machine comprising a rotating carrying-disk having a series of mandrels arranged radially, each adapted to receive and hold a blank and to present it to the kerfing-saws, mechanism for causing the said mandrels to each make a partial rotation on its longitudinal axis; and kerfing-saws, working through blank-holders, substantially as and for the purpose set forth.

12. A kerfing-machine comprising a carrying-disk having radial mandrels rotatable on their axes, adapted to hold blanks each of said mandrels being provided with a retaining-spring, and a cam-pin; a fixed cam-piece placed in the path of the cam-pins and adapted to so act upon the said pins as to turn their respective mandrel to such a position that the saws will cut the kerfs at the desired angles, substantially as and for the purpose set forth.

13. In a kerfing-machine, the combination with a rotating carrier having peripheral pockets for receiving eyelets, of a plurality of kerfing-saws located successively in the path of movement of said carrier, and means for imparting a partial rotation to said eyelets at a point intermediate the operative contact of said saws.

14. In a kerfing-machine, the combination with a rotary carrier having peripheral pockets to receive the blanks, means located without and independent of the carrier for holding the blanks thereupon, and means for discharging the blanks after they are kerfed.

In testimony whereof I have signed my name to this specification, in the presence of two subscribing witnesses, on this 2d day of February, A. D. 1900.

GEORGE A. HOLMES.
